US00D328582S

United States Patent [19]

Covert et al.

[11] Patent Number: Des. 328,582

[45] Date of Patent: ** Aug. 11, 1992

[54] PNEUMATIC TIRE TREAD AND BUTTRESS

4-Rear Street Tire, third row down from top, center of page.

[75] Inventors: Darrell E. Covert, Strassen, Luxembourg; Paul B. Maxwell, Stow, Ohio

Primary Examiner—James M. Gandy
Attorney, Agent, or Firm—Thomas P. Lewandowski

[73] Assignee: The Goodyear Tire & Rubber Company, Akron, Ohio

[57] CLAIM

[**] Term: 14 Years

The ornamental design for a pneumatic tire tread and buttress, as shown and described.

[21] Appl. No.: 595,950

DESCRIPTION

[22] Filed: Oct. 11, 1990

FIG. 1 is a perspective view of a pneumatic tire tread and buttress showing our new design, it being understood that the pattern is repeated uniformly throughout the circumference of the tread and buttress, the broken lines being for illustrative purposes only and form no part of the claimed design;

[52] U.S. Cl. D12/147

FIG. 2 is a perspective view thereof taken from the opposite side;
